DESIGN FOR AN ART PROJECTOR

James W. Decker, New York, N. Y.

Application June 13, 1946, Serial No. 130,675

Term of patent 14 years

(Cl. D61—1)

To all whom it may concern:

Be it known that I, James W. Decker, a citizen of the United States, residing at Manhattan Borough, in the city, county, and State of New York, have invented a new, original, and ornamental Design for an Art Projector, of which the following is a specification, reference being had to the accompanying drawings, forming a part thereof, in which:

Fig. 1 is a side perspective view, Fig. 2 is a rear perspective view, and Fig. 3 is a plan view of the art projector, showing my new design.

I claim:

The ornamental design for an art projector, as shown.

JAMES W. DECKER.
